UNITED STATES PATENT OFFICE.

HARRY L. WILLIS, OF CHICAGO, ILLINOIS, ASSIGNOR TO UNION SPECIAL MACHINE COMPANY, OF CHICAGO, ILLINOIS, A CORPORATION OF ILLINOIS.

THREAD CUTTER FOR SEWING MACHINES.

Application filed January 2, 1924. Serial No. 683,976.

To all whom it may concern:

Be it known that I, HARRY L. WILLIS, a citizen of the United States, residing at Chicago, in the county of Cook, State of Illinois, have invented certain new and useful Improvements in Thread Cutters for Sewing Machines, of which the following is a description, reference being had to the accompanying drawings, and to the figures of reference marked thereon.

The invention relates to new and useful improvements in sewing machines, and more particularly to thread cutters adapted to cut a thread extending from a stitched article to the stitching mechanism.

Prior to my invention, it has been the practice to provide certain types of machines with a thread cutter which is attached to the presser bar and so arranged that the thread extending between a stitched article and the stitching element may be drawn across the cutter for severing the thread. In certain types of machines, a thread cutter of this character cannot be used as, for example, in a sewing machine having a feed dog working above the material and along side of the presser foot, wherein said feed dog is operated through a connection extending in rear of the presser foot and beneath the work support where it is attached to a feed bar.

An object of the present invention is to provide a thread cutter for a machine of the above type, and in carrying out the invention, I have provided means whereby a thread cutter may be mounted on the shank portion of the upper feed dog.

In the drawings, which show by way of illustration one embodiment of the invention:

Figure 1 is a perspective view showing a machine embodying my invention;

Fig. 2 is a top plan view of the upper feed dog with my improved thread cutter attached thereto;

Fig. 3 is a top plan view of the upper cutting section;

Fig. 4 is a top plan view of the lower thread cutting section;

Fig. 5 is a top plan view of the feed dog with the thread cutter removed;

Fig. 6 is a side view of the upper feed dog with my improvements applied thereto;

Fig. 7 is a sectional view on the line 7-7 of Fig. 4.

The machine to which my invention is applied is an ordinary flat bed machine having a feed dog beneath the work support which projects through a slot in the throat plate for engagement with the material for feeding the same. Cooperating with this lower feed dog is an upper feed dog which is carried by a supporting shank attached to a feed bar beneath the work support, which shank extends from beneath the work support above the same and around the rear of the presser foot, and supports a feed dog preferably formed integral therewith which lies alongside of the presser foot and cooperates with the lower feed dog above the work support. Such a machine is shown in Patent No. 591,517, granted to R. G. Woodward, October 12, 1897, and consists of a work support 1 having a lower feed dog 2 and presser foot 3 having a needle hole 4 therethrough through which the needle reciprocates. Said presser foot is carried by a presser bar 5.

Cooperating with this lower feed dog 2 is an upper feed dog 6 which consists of a shank portion 7 with which the feed portion 6 is integrally formed. This shank portion 7 is curved so as to extend around the heel or rear of the presser foot 3 and has a depending portion 8 which extends through a slot in the work support and is attached to a lower feed bar after the manner shown in the patent referred to above.

The shank portion of the feed dog is provided with two threaded openings 9 and 10. The thread cutter is composed of two members 11 and 12. The member 11 is the lower member and is attached directly to the U-shaped portion 7 of the shank of the upper feed dog. Said lower portion of the cutter is provided with two openings 13 and 14 which are adapted to register respectively with the openings 9 and 10 in the shank of the feed dog. Said lower portion has a V-shaped notch 15, the edge 16 of which is beveled as shown in Fig. 7.

The upper member 12 of the thread cutter has a beveled edge 17; also two openings 18 and 19 which are adapted to register respectively with the openings 13 and 14. These openings 18 and 19 are slightly elongated. The screw 20 is adapted to pass through the elongated opening 18, the opening 13, and is threaded into the opening 9. A threaded bolt 21 passes through the elongated opening 19 and is threaded into the opening 10.

gated opening 19, the opening 14 and is threaded into the opening 10. A nut 22 is threaded onto this bolt and serves as a means for clamping the two sections of the 5 thread cutter together and against the shank of the upper feed dog. This threaded bolt 21 is also used for supporting the feed dog in its various adjusted positions as to height after the manner set forth in the Woodward patent, and it performs the function in 10 in the present instance through the nut 22 of rigidly supporting the members of the thread cutter.

The two sections are so arranged, when 15 attached to the feed dog, that the beveled edge 17 overlies and intersects the beveled edge 16, thus forming a V-shaped opening into which the thread may be drawn for bringing it against these beveled edges for 20 the purpose of severing the thread.

In stitching an article, the operator runs the article through from beneath the presser foot and, at the same time, forms a chain of thread. Then the article is lifted by the operator, brought forward over top of the 25 thread cutter, and the thread laid into said notch in the thread cutter. A slight pull on the chain will draw it against the beveled edges of the thread cutter and sever the same.

The elongated openings in the upper member of the thread cutter afford a means for adjusting the upper section as it is ground to keep the beveled edge sharp, and thus 35 bring the beveled edges into proper cooperation for severing the thread. It will be understood, of course, that, when the thread is cut, the machine is not running and, therefore, the upper feed dog is stationary, 40 and this enables the thread to be laid into the thread cutter and severed without any difficulty. By having the threaded bolt 21, as well as the threaded screw 20, for securing the two members of the cutter together to 45 the feed dog, I am able to provide a very rigid support for the thread cutting members, wherein said members will not be disturbed in any way by pulling up the thread thereagainst when the thread is to be severed.

50 It is obvious that minor changes in the

details of construction and the arrangement of the parts may be made without departing from the spirit of the invention as set forth in the appended claims.

What I claim as new is:—

1. In a sewing machine, the combination with a presser foot, an upper feed dog supported beneath the work support and extending around in rear of the presser foot, of a thread cutter mounted on said feed dog and disposed so that the thread leading from the stitching mechanism to a stitched article may be drawn across said thread cutter for severing the thread. 55

2. In a sewing machine, the combination with a presser foot, an upper feed dog extending along side of said presser foot and supported by a shank extending in rear of the presser foot, of a thread cutter including two cooperating sections rigidly secured to the shank on the feed dog and disposed so as to form a V-shaped cutting notch facing rearwardly and adapted to receive the thread extending from the stitching mechanism to a stitched article and laid thereagainst by the operator. 70

3. In a sewing machine, the combination with a presser foot, an upper feed dog including a feeding portion extending along side of the presser foot, a shank portion extending in rear of the presser foot and carried beneath the work support, a thread cutter including a lower section conforming to the shank of the feed dog in rear of the presser foot, an upper section likewise conforming to the section of the feed dog in rear of the presser foot, means for securing said sections of the cutter to the shank of the feed dog, said lower section having a projecting portion shaped so as to form one wall of a V-shaped notch with its edges beveled, said upper section being shaped so as to form the other wall of a V-shaped notch having its edge beveled, said V-shaped notch opening rearwardly so that an operator may draw the thread connecting the stitching mechanism to a stitched article into said notch for the severing of the thread. 85 95

In testimony whereof, I affix my signature.
HARRY L. WILLIS.
